CLAIM

The ornamental design for a handheld brush, as shown and described.

DESCRIPTION

FIG. 1 is a front perspective view of an ornamental design for a handheld brush according to the present invention; FIG. 2 is a rear perspective view of the handheld brush of FIG. 1;

FIG. 3 is a front elevational view of the handheld brush of FIG. 1;

FIG. 4 is a rear elevational view of the handheld brush of FIG. 1;

FIG. 5 is a left side elevational view of the handheld brush of FIG. 1;

FIG. 6 is a right side elevational view of the handheld brush of FIG. 1;

FIG. 7 is a top plan view of the handheld brush of FIG. 1; and,

FIG. 8 is a bottom plan view of the handheld brush of FIG. 1.

The broken lines shown are included for the purpose of illustrating portions of the handheld brush that form no part of the claim.

1 Claim, 8 Drawing Sheets
